SURFACE CLEANING DEVICE EMPLOYING
LIQUID CLEANING AGENT

Vernon H. Goldsmith, West Palm Beach, Fla.

Application March 1, 1945, Serial No. 580,313

4 Claims. (Cl. 15—130)

1

This invention relates to an improved cleaning device, and more particularly to a cleaning device provided with means for the even distribution of a cleaning liquid upon the surface to be cleaned and the removal of the liquid during or at the completion of the cleaning operation.

One of the objects of the present invention is to provide a cleaning device of the character described, which may be connected to a source of cleaning liquid and is constructed in such a manner that the liquid will be evenly distributed by the device upon the surface to be cleaned.

Another object of the present invention is to provide a cleaning device of the character described, which may be connected to a source of suction and is constructed in such a manner that a liquid can be removed by the force of suction from the surface being cleaned, either during or at the completion of the cleaning operation.

Still another object of this invention is to provide a cleaning device of the character described, provided with a swivelly mounted handle designed to assist in reaching inaccessible places.

A further object of the present invention is to provide a cleaning device of the character described which is designed to permit the instantaneous application and removal of the wear pad which remains in contact with the surface which is to be cleaned during the cleaning operation.

With these and other objects in view, which will be apparent from the subsequent description, the present invention resides in providing a cleaning device which can be attached to a source of cleaning liquid, such as water, and a source of suction. This construction is highly advantageous because it enables an operator to apply a liquid to the surface to be cleaned and to remove the liquid from the surface during or after the cleaning operation, without interfering with the cleaning operation.

The cleaning device comprises a head attached to a handle by means of which it is connected to a source of cleaning liquid and the source of suction. The head should be shaped to conform to the type of surface to be cleaned, and may be of any desirable form to reach inaccessible places.

It is provided with a perforated partition which supports a porous cushion which is positioned between it and a porous wear pad. The liquid is evenly distributed through these perforations and porous pads upon the surface to be cleaned and the operation can be reversed by the

2

force of suction. The wear pad may be readily detached from the head to afford economical replacement, and is made of a porous material such as sponge rubber. It affords a most efficient means of effecting a completely dry surface after the washing operation has been completed.

The handle is swivelly mounted upon the head to assist the operator in reaching the inaccessible places. If desired, the handle can be removed from the head for shipment, storage, or other purposes. The handle may be either straight or curved, depending upon the type of cleaning operation for which it is especially suited and is preferably provided with means, to control the flow of cleaning liquid and the application of suction, which are readily accessible to the operator.

The drawings disclose a single form of the cleaning device which may be used to effect the objects of the present invention.

In the drawings:

Figure 1 is a side elevational view of the cleaning device.

Figure 2 is a plan view of the cleaning device.

Figure 3 is a side elevational view, in section, of the head and a portion of the handle of the device shown in Figures 1 and 2.

As shown in the drawings, the cleaning device comprises a head 1 operatively connected to a tubular handle 2 by means of a cylindrical member 3, the reduced lower portion of which snugly fits a flanged aperture in the dome of the head 1. The tubular handle 2 is provided with a grip 4.

A pipe 5 is concentrically positioned within the tubular portion of the handle 2 and is connected to a source of cleaning liquid, such as water, by means of a valve fitting 6 and a conduit 7.

The tubular portion of the handle 2 is connected to a source of suction by means of the fitting 8 and a conduit 9. A control switch 10 is mounted on the handle 2, adjacent the grip 4 and is connected by a wire 11 to the power unit which operates the suction pump.

Concentrically positioned within the cylindrical member 3 is a socket 12 which is connected thereto by the perforated web member 13. The socket 12 is adapted to receive the lower extremity of the pipe 5, and is provided with a discharge duct 14 which connects the pipe 5 to the upper compartment 15 of the head 1. The perforations in the web member 13 also serve as communicating channels between the tubular portion of the handle 2 and this upper compartment 15.

As best shown in Figure 3, the lower portion of the handle 2 is provided with an annular flange 16 secured by screws 17. The handle 2 may be swivelly mounted on the member 3 by insertion of the annular flange 16 into the annular groove 18. The handle 2 is also provided with a shot pin 19, carried by a spring member 20 which is mounted on the exterior surface of the handle 2. Swiveling of the handle 2 may be prevented by insertion of the shot pin 19 in one of a plurality of sockets 21, circumferentially arranged in the member 3.

A perforated partition 22 forms the base of the compartment 15. A porous wear pad 23 is secured to the bottom of the head 1 by means of a retaining ring 24, which may be in the form of a spring, rod, or strap of suitable design. The retaining ring is designed to permit instantaneous removal of the wear pad.

A porous cushion 25 is positioned between the partition 22 and the wear pad 23. It is held in place by the flanged extremity 26 of the head 1.

The wear pad 23 and cushion 25 may be of any suitable porous material which will evenly distribute the cleaning liquid upon the surface which is to be cleaned, and through which the liquid can be withdrawn by the force of suction. Preferably a porous material such as sponged rubber is employed.

At the commencement of the cleaning operation the valve 6 is opened to admit liquid under pressure to the pipe 5 from which it passes through the discharge duct 14 into the compartment 15. The liquid then flows through the perforations in the partition 22 and the porous pads 23 and 25 by means of which it is evenly distributed on the surface to be cleaned. When a sufficient quantity has been discharged the valve 6 is closed.

After a given portion of the cleaning operation has been completed, or the liquid is no longer suitable for use, suction is created by closing the switch 10 and the liquid is withdrawn from the working surface through the pores of the pads 23 and 25 and the perforations in the partition 22. The liquid then passes through the channels in the web 13 and the tubular portion of the pipe 2 to the conduit 9 through which it is discharged.

This operation may be repeated as many times as is necessary to complete the cleaning operation without requiring the operator to discontinue the cleaning operation. In the event that an inaccessible place is to be cleaned, the handle 2 may be swiveled on the member 3 to a more convenient position by withdrawing the shot pin 19 from the socket 21 in which it is positioned and inserting it in a more suitable socket.

From the foregoing, it will be appreciated that the described cleaning device combines several individual steps of the cleaning operation, such as the application of liquid to the cleaning surface and its removal after the scrubbing operation. Moreover, the liquid is more evenly distributed and more rapidly removed by this device than in the familiar hand operation. While, in describing this device reference has been made to particular material, apparatus and conditions it should be understood that the invention is not specifically limited thereto, but may be varied to include equivalent material, apparatus and conditions.

I claim:

1. A cleaning device comprising a hollow head, a tubular member in communication therewith, a tubular handle mounted on the said member, means to attach the handle to a source of suction, a pipe positioned within the handle, means

to attach the pipe to a source of liquid supply, a socket concentrically positioned in the said tubular member and attached thereto by a perforated web, said socket adapted to receive the lower extremity of the pipe, a discharge duct in said socket, said duct and web perforations communicating with the upper portion of the head, a laterally extending perforated partition in the head, a porous wear pad attached to the lower portion of the head and closing the head to form a chamber, a porous cushion positioned between the wear pad and perforated partition, means to control the introduction of fluid to the chamber through said pipe and to pass such fluid through the permeable wear pad onto the surface to be cleaned, and other means to control the suction applied within the tubular handle and head to remove the fluid from the surface through said pad and the chamber into the handle.

2. A cleaning device comprising a hollow head, a cylindrical member mounted on the top thereof, a tubular handle swivelly mounted on the said member, means to attach the handle to a source of suction, a pipe positioned within the handle, means to attach the pipe to a source of liquid supply, a socket concentrically positioned in the said cylindrical member and attached thereto by a perforated web, said socket being adapted to receive the lower extremity of the pipe, a discharge duct in said socket in communication with the pipe, said duct and web perforations communicating with the upper portion of the head, a perforated plate extending across the head near the base thereof, a porous wear pad attached to the lower portion of the head and closing the head to form a chamber, and a porous cushion positioned between the wear pad and perforated partition, means to control the introduction of fluid to the chamber through said pipe and to pass such fluid through the permeable wear pad onto the surface to be cleaned, and other means to control the suction applied within the tubular handle and head to remove the fluid from the surface through said pad and the chamber into the handle.

3. A cleaning device comprising a hollow head, a cylindrical member mounted on the top thereof, a tubular handle swivelly mounted on the said member, means to attach the handle to a source of suction, a switch mounted upon the handle to control the application of suction, a pipe positioned within the handle, means to attach the pipe to a source of liquid supply, a valve mounted on the handle to control the flow of liquid, a socket concentrically positioned in the said cylindrical member and attached thereto by a perforated web, said socket being adapted to receive the lower extremity of the pipe, a discharge duct in said socket in communication with said pipe, said duct and web perforations communicating with the upper portion of the head, a perforated partition extending across the head near the base thereof, a porous wear pad attached to the lower portion of the head and closing the head to form a chamber, and a porous cushion positioned between the wear pad and perforated partition.

4. A cleaning device comprising a hollow head constituting a chamber, a permeable pad attached to the head and forming a permeable outer wall of the chamber, a perforated transverse rigid partition in the chamber parallel to said wall, a resilient cushion disposed between the wall and partition, a tubular handle having

a connection with the head and communicating with said chamber, a pipe carried by the handle and also communicating with said chamber, means to connect the tubular handle and pipe respectively to a source of suction and a source of cleaning fluid supply, means to control introduction of the fluid through said pipe into the chamber and thence through said permeable wall onto a surface to be cleaned, and other means to control application of suction in said handle and chamber to remove the fluid from said surface through said wall, chamber and handle.
